UNITED STATES PATENT OFFICE

160,508

DOOR GRILLE OR THE LIKE

John E. Lindstrom, Aurora, Ill.

Application December 23, 1949, Serial No. 6,810

Term of patent 14 years

(Cl. D13—2)

To all whom it may concern:

Be it known that I, John E. Lindstrom, a citizen of the United States and a resident of the city of Aurora, in the county of Kane and State of Illinois, have invented a new, original, and ornamental Design for a Door Grille or the like, of which the following is a specification, reference being had to the accompanying drawing, forming part thereof.

Figure 1 is a plan view of a door grille or the like embodying my new design, and Figure 2 is an edge view of the same.

I claim:

The ornamental design for a door grille or the like, as shown.

JOHN E. LINDSTROM.
